LIQUID DISPENSER

Theodore M. Costakos, Minneapolis, Minn.

Application March 30, 1949; Serial No. 84,375

12 Claims. (Cl. 222—128)

1

In my previous invention, Patent No. 2,457,531, issued Dec. 28, 1948, a cupped valve body is incorporated in the bottom of a container adapted to hold a supply of liquid to be dispensed. This valve body provides a sump chamber and is formed with a downwardly leading discharge bore. Associated with said valve body is a lift valve including a valve sleeve slideable in said sump chamber and a valve plug slideable in said discharge bore. This lift valve further includes a valve stem which extends downwardly through said discharge bore. Valve lifting means associated with said valve stem provides for the raising of the lift valve by means of a receptacle into which a charge of liquid is to be dispensed. A tubular stand having a socketed footing in the cupped valve body supports a mounting for vertical adjustment thereon, said mounting, in turn, slidably guiding a closure cap for the upper end of the valve sleeve and variably limiting its gravitating descent to selected levels spaced above the downwardly retracted valve sleeve. When the lift valve is elevated, the closure cap is engaged and lifted by the valve sleeve. The sump chamber of the valve body together with the valve sleeve at the point of its engagement with the closure cap constitutes a vessel for a measured charge of liquid received thereby from the supply in the container, the quantity of which is determined by the vertical adjustment of said mounting on said stand in selection of the limit of descent of said closure cap. Following the engagement of the ascending valve sleeve with the vertically movable closure cap, the valve plug is withdrawn from the discharge bore in the valve body to release through said bore the charge of liquid trapped in said measuring vessel by said closure cap. A funnel member embodied in the valve lifting means directs the released charge of liquid into the receptacle employed to actuate said means.

An object of my present invention is to provide an improved construction in dispensers which is more simple, less costly and more readily cleansed than previously devised constructions, a more specific object being to provide an improvement over my said first devised construction wherein a simplified form of closure member is adapted to eliminate, among other things, the stand and the adjustable mounting thereon for guiding the closure member.

Another object of my present invention is to provide an improved construction in liquid dispensers, wherein wasteful dripping of the liquid between dispensing operations is effectively fore stalled, a more specific object being to provide an improvement over my said first devised construction, wherein the funnel member for directing the measured charges of liquid into a

receptacle is valved at the bottom thereof to trap in said funnel member the drip from the liquid measuring valve after an actuation thereof and then release the accumulated drip into the valve-actuating receptacle employed to effect the succeeding actuation of said measuring valve.

Other objects of the invention reside in the novel combination and arrangement of parts and in the details of construction hereinafter illustrated and/or described.

In the drawings, Fig. 1 is a side elevational view of a liquid dispenser constructed in accordance with my present invention, a portion of the container for a supply of liquid to be dispensed being broken away and showing in elevation a portion of the valve mechanism employed in delivering measured charges of liquid from the container; Fig. 2 is a fragmentary sectional view, taken as on the line 2—2 of Fig. 1, showing in plan the valve mechanism for delivering liquid from the container; Fig. 3 is a perspective view in detail of the valve mechanism shown in Fig. 1, said view being partially broken away to reveal the internal construction of said mechanism; Fig. 4 is a vertical sectional view illustrating the parts of said valve mechanism in their relative disposition at one stage in the operation of said mechanism, said parts being arranged to deliver a measured charge of liquid of minimum quantity; Fig. 5 is a view similar to Fig. 4 showing the same parts similarly arranged but differently relatively disposed at a subsequent stage in the operation of the device; Figs. 6 and 7 are views similar to Figs. 4 and 5, respectively, but with the closure plate for the valve sleeve inverted to effect the delivery of liquid in charges of maximum quantity.

Referring to the accompanying drawings, it will be seen that the illustrated embodiment of my present invention includes a container A for a supply of liquid, such as cream, to be dispensed in measured quantities into receptacles, such as a coffee cup 10, shown in dotted lines in Fig. 3, or such as an individual cream pitcher 11, shown in dotted lines in Fig. 1. The container A consists of a double-walled cylindrical body 12 having a bracket 13 secured to one side thereof and formed with a depending stud 14 removably socketed in the upper end of a tubular leg 15 standing on a base member 16. Supported on the leg 15, the body 12 of said container A is held axially upright in a position elevated to accommodate the placement of a receptacle beneath the same. Said container A is open at the top and normally closed by a lid 17 which is removable from the container to admit of the introduction of liquid thereto and to provide access to the interior thereof.

A valve mechanism B includes a valve body 18 of cup-like formation incorporated in the bottom of the container A, the upwardly opening cavity in said cupped valve body 18 providing a sump chamber 19 for the liquid supply chamber 20 in the container A. Depending axially from the valve body 18 is a boss 21 which has an axial discharge bore 22 therein leading downwardly from the sump chamber 19.

A lift valve b fitted to the valve body 18 comprises an axially upright valve sleeve 23 slidable vertically in the sump chamber 19, an axially upright valve plug 24 slidable downwardly into and upwardly out of the discharge bore 22, and a valve stem 25 depending from the valve plug 24 and extending downwardly through said discharge bore 22, said valve stem 25 being removably threadedly connected with said valve plug 24 and disposed coaxially with respect thereto. Radial arms 26 fast at their outer ends to the valve sleeve 23 and fast at their inner ends to the valve plug 24 connect said valve sleeve 23 and valve plug 24 together leaving an annular space intervening between them.

The lift valve b is self-movable downwardly by gravity to effect the retraction of the valve sleeve 23 into the sump chamber 19 along with the lowering of the valve plug 24 into the discharge bore 22, said lift valve b being raised, as will later appear, to effect the upward projection of said valve sleeve 23 from the sump chamber 19 along with the upward withdrawal of said valve plug 24 from said discharge bore 22.

To limit the gravitating descent of the lift valve b and to render the valve mechanism B liquid-tight when said lift valve b is in its lowermost position, the lower portion of the valve plug 24 is externally beveled as at 27, and said discharge bore 22 is formed with a correspondingly beveled reduction 28, the same constituting a seat for said beveled portion 27 of said valve plug 24.

Normally resting on the bottom 29 of the container A is a closure plate 30 having an intermediate cap portion 31 and marginal end portions 32. This closure plate 30 is provided at its extremities with flanges 33 extending at right angles relative to the plate proper, said flanges forming legs for the plate 30. Said closure plate 30 may be inverted either to bring the legs 33 thereon into an operative position resting on the bottom 29 of the container A and supporting the closure plate 30 at a relatively high elevation with respect to the bottom of the container (Figs. 1 and 6), or to bring said legs 33 into an upwardly extending position of disuse, whereby the closure plate proper rests directly upon the bottom 29 of the container at a relatively low elevation with respect thereto (Fig. 4). The intermediate cap portion 31 of the closure plate 30 is of an area sufficiently large to cover the upper end of the valve sleeve 23 and close the same at the top thereof against the influx thereinto of liquid from the chamber 20 of the container A. Said cap portion 31 of the closure plate 30 is formed with an aperture 34 centrally thereof in which is slidably received a centering post 35 upstanding from the valve plug 24. This centering post 35 retains the closure plate 30 in position transversely of the container A, wherein said cap portion 31 of said plate is disposed directly above the valve sleeve 23 with the marginal portions 32 of said plate 30 overreaching the bottom 29 of the container A at opposite sides of said valve sleeve 23. In this connection, it is to be noted that in the normal retracted position of the valve

sleeve 23, the upper edge of said sleeve is downwardly spaced from said closure plate 30 in both of its said high and low positions to admit liquid from the container into said sleeve 23. In either of said high and low positions of the closure plate 30, the cap portion 31 thereof is engaged by the upper edge of the valve sleeve 23 and lifted by said sleeve as the lift valve b is raised, such engagement of said valve sleeve 23 with said closure cap 30 occurring before the withdrawal of the valve plug 24 from the discharge bore 22 in the valve body 18. Thus, all of the liquid contained in the sump chamber 19 and in the upwardly projected valve sleeve 23, at the time of engagement of said valve sleeve 23 with said closure plate 30, becomes a trapped charge of liquid in quantity of accurate measurement ready to flow out of the discharge bore 22 as soon as said bore is cleared by the valve plug 24. In other words, at the stage of ascent of the valve sleeve 23, just prior to the engagement of said sleeve with the closure plate 30, the sump chamber 19 and the upwardly projected valve sleeve 23 form a vessel which is filled from the liquid supply and measures out a definite quantity of the liquid, said measured quantity of the liquid being segregated in said vessel from the main supply of liquid in the container by the closure plate 30 for subsequent delivery to occur upon the clearing of the discharge bore 22 by the valve plug 24.

As previously indicated, the lift valve b is elevated through the medium of a receptacle into which a measured charge of liquid is to be dispensed from the discharge bore 22 of the valve body 18. To this end, I provide means on the valve stem 25 adapted to be engaged by the rim of a receptacle and lifted to elevate said lift valve b. Said means includes a breast member C embodying a tubular filler element 36 in the form of a funnel downwardly tapered interiorally and exteriorly thereof, the upper open end of said filler element 36 being relatively wide to catch the liquid flowing from the discharge bore 22 in the valve body 18. At the bottom of the filler element 36 is a relatively narrow valve opening 37 for the egress of liquid from said element 36. This filler element 36 has a mounting sleeve 38 therefor coaxially disposed with respect thereto and is connected with said mounting sleeve 38 by means of radial arms 39 extending from the wall of said element 36 to said sleeve 38. This mounting sleeve 38 is slidably mounted on the valve stem 25, the valve plug 24 being engaged by the upper end of said sleeve 38 to limit the upward movement of the filler element 36 relative to said valve stem 25. The reverse or downward movement of said filler element 36 with respect to the valve stem 25 is limited by the engagement of the bottom of the element 36 with a valve head 40 on the valve stem 25 at the lower end thereof. In this connection, it is to be noted that when said valve head 40 is thus engaged by the filler element 36, the valve opening 37 in said element is closed by said valve head 40.

The external tapering of the filler element 36 enables its lower marginal portion to be received within the mouth of a relatively small receptacle such as an individual cream pitcher, while at the same time providing for the engagement of the rim of such receptacle with a higher portion of said filler element 36, whereby the filler element may be caused to be lifted by the receptacle upon an upward thrust thereof. The initial upward movement of the filler element 36, im-

parted thereto by the thrust of a receptacle slides said filler element upwardly on the valve stem 25. Thus moved along said stem 25, the filler element 36 clears the valve opening 37 therein from the valve head 40 on the valve stem 25 and brings the upper end of the mounting sleeve 38 against the valve plug 24. Thereafter, the continuing upward movement of said filler element 36 lifts the lift valve b and continues so to do until the rim 36a of said element 36 strikes the bottom of the valve body 18. This engagement of the filler element 36 with said valve body, of course, arrests the upward actuating thrust of the liquid-receiving receptacle and the lifting of the lift valve b.

In addition to the filler element 36, I have further embodied in the breast member C a pair of contact arms 41 (Fig. 3) which are removably attached to the filler element 36 in position extending radially outward therefrom above the lower marginal portion thereof. These contact arms 41, while not interfering with the application of a relatively small receptacle to the filler element 36, are engageable by the rim of a receptacle which is too large to engage the outer tapered surface of said filler element 36 and contact therewith to lift said element. Said contact arms 41 are threadedly connected at their inner ends with a mounting ring 42 which encircles the filler element 36 and which is removably held in place thereon by screwing the arms 41 into the mounting ring 42 to advance their inner extremities 43 into seat-forming cavities 44 in the wall of said filler element 36.

Fig. 4 of the drawing shows the lift valve b lifted, as by a receiving receptacle (not shown) thrust upwardly against the filler element 36, and raised to an elevation wherein the upper edge of the valve sleeve 23 makes contact with the closure plate 30 in its low normal disposition with the plate proper resting directly upon the bottom 29 of the container A and with the legs 33 on said plate extending upwardly in disuse. At this stage in the operation of the mechanism, the valve opening 37 in the filler element 36 will have been opened to deliver into the receiving receptacle any liquid that may have drained or dripped into said filler element 36 after the preceding operation, and to ready said filler element 36 for delivery of the next measured charge of liquid to flow into it from the container A.

Fig. 5 shows the lift valve b at its upper limit of movement, wherein the liquid trapped by the closure plate 30 in the measuring vessel formed by the sleeve 23 and sump chamber 19 is free to flow out of the discharge bore 22, now cleared by the valve plug 24, into the filler member 36, and thence through the valve opening 37 in said filler member 36 into the receptacle upwardly pressed against the breast member C to receive such liquid.

Fig. 6 corresponds with Fig. 4, except that the closure plate 30 is shown inverted to bring the legs 33 thereon to bear upon the bottom 29 of the container A and thereby hold said closure plate 30 in its relatively high position as compared with the relatively low position thereof shown in said Fig. 4. This difference in the normal disposition of the closure plate 30, as previously explained, results in measuring out the liquid in charges of the lesser or the greater quantity. Fig. 7, like Fig. 5, shows the lift valve b at the limit of its upward movement.

For sanitary reasons and to keep the mount-

ing sleeve 38 free to slide relative to the valve stem 25, the valve plug 24 is formed with a depending annular flange 45 defining a recess 46 in the bottom of said plug 24. The upper end of said mounting sleeve 38 plays up and down within the depth of said recess 46 free from contact with the inner surface of said flange 45. Thus, none of the liquid leaving the discharge bore 22 will contact the upper end of the mounting sleeve 38 or the valve stem 25 above said sleeve. Preferably the flange 45 will be beveled internally, as at 47, in opposition to the seating bevel 27 to provide a knife edge 48 for minimizing the accumulation of liquid at the bottom of the valve plug 24 to drip therefrom into the filler element 36.

The instant structure is readily cleansed, the few parts thereof being easily disassembled for such purpose. After the container A has been emptied of its supply of liquid, the valve stem 25 is unscrewed from the valve plug 24 and the breast member C removed from said stem 25. From the top of the container A, the closure plate 30 and lift valve b are removed therefrom. Thus, the container and said removed parts are individually accessible throughout for the convenient and thorough cleansing thereof. Reversing the order of disassembly, the cleansed parts are easily reassembled.

Changes in the specific form of my invention, as herein described, may be made within the scope of what is claimed without departing from the spirit of my invention.

Having described my invention, what I claim as new and desire to protect by Letters Patent is:

1. In a dispenser, a container for a supply of liquid, valve mechanism adapted to dispense from the container successive charges of liquid in measured quantities, said valve mechanism comprising a cuffed valve body in the bottom of the container providing a sump chamber, said valve body being formed with a discharge bore therein opening downwardly from said sump chamber, a lift valve movable downwardly by gravity and including an axially upright valve sleeve slidable in the sump chamber for downward retraction thereinto and for upward projection therefrom, and a valve stem connected with said valve sleeve and extending downwardly through said discharge bore, means associated with the valve stem beneath the container for elevating the lift valve, said lift valve further including a valve plug connected with said valve stem and downwardly movable into said bore to obstruct the same upon the descent of the lift valve and upwardly movable out of said bore to clear the same upon the elevation of the lift valve, a closure plate having an intermediate cap portion overreaching the upper end of the valve sleeve and having marginal portions adapted to rest on the bottom of the container at either side of said sleeve normally to support said cap portion of said plate upwardly spaced from said upper end of the retracted sleeve, said cap portion of the closure plate being adapted to be engaged by the upper end of the ascending valve sleeve and to close the same, said closure plate being lifted from the bottom of the container by the valve sleeve upon its engagement with said cap portion of said closure plate, said sump chamber and valve sleeve forming a vessel for measuring liquid flowing thereinto from said container, said vessel being sealed off from the liquid supply upon engagement of said valve sleeve with said closure plate, thereby to trap within said ves-

sel its measured charge of liquid, the clearing of said discharge bore by said plug following the engagement of said valve sleeve with said closure plate to release from the dispenser said measured charge of liquid.

2. A dispenser, as defined in claim 1, including a centering stem for the closure plate, upstanding from and movable with the valve sleeve, said closure plate having an aperture therein slidably receiving said centering stem.

3. A dispenser, as defined in claim 1, including legs on the closure plate at one side thereof, said closure plate being adapted to be inverted either to bring said legs to bear on the bottom of the container or to bring them into upwardly projecting position of disuse, thereby to change the normal disposition of the closure plate from a relatively low elevation to a relatively high elevation and thus provide for the variable measurement of charges of liquid to be delivered from the dispenser.

4. A dispenser, as defined in claim 1, including means on the closure plate adapted to support it on the bottom of the container at a relatively high elevation providing a second normal disposition thereof to effect measurement of the charges of liquid in relatively large quantity.

5. In a dispenser, a container for a supply of liquid, valve mechanism adapted to dispense from the container successive charges of the liquid, said valve mechanism comprising a valve body in the bottom of said container, said body having a discharge bore therein opening downwardly therefrom, a lift valve including a valve plug downwardly movable to obstruct said discharge bore upon the gravitating descent of said lift valve and upwardly movable to clear said discharge bore upon the elevation of said lift valve, a valve stem extending downwardly from said valve plug and out of said discharge bore, said valve stem having a valve head thereon at the lower portion thereof, means associated with the valve stem for elevating said lift valve, said means including a breast member adapted to be engaged by the rim of a receptacle into which a charge of liquid is to be dispensed, said breast member embodying a filler element open at the top thereof for the reception of liquid from said discharge bore and having a valve opening in the bottom thereof for the egress of such liquid from said element into said receptacle, said filler element being mounted on said stem to descend therewith by gravity, said valve head being adapted to be engaged by the descending filler element to arrest its descent and to close the valve opening therein, and stop means adapted to arrest the lifting of said filler element relative to said stem after the valve opening in the ascending filler element has cleared the valve head on said stem.

6. A dispenser, as claimed in claim 5, in which the filler element of the breast member is of downwardly tapered funnel-like formation for the reception of its lower portion by a receptacle into which liquid is to be dispensed and for the circumferential engagement of said element by the rim of such receptacle.

7. A dispenser, as claimed in claim 5, in which the breast member includes at least one contact arm radiating from the filler element for engagement by the rim of a receptacle into which liquid is to be dispensed.

8. A dispenser, as claimed in claim 5, in which the filler element of the breast member is of downwardly tapered funnel-like formation for

the reception of its lower marginal portion by a relatively small receptacle into which liquid is to be dispensed and for circumferential engagement of said element by the rim of such receptacle, said filler element having at least one contact arm radiating therefrom at an elevation above said lower marginal portion thereof for engagement by the rim of a relatively large receptacle into which liquid is to be dispensed.

5 9. A dispenser, as claimed in claim 8, in which the one at least of said contact arms is adapted to be readily attached to said filler element for use or detached therefrom when its use in connection with relatively large receptacles is not required.

10 10. A dispenser, as claimed in claim 5, in which the filler element is mounted on a coaxially disposed sleeve, and said sleeve is slidably mounted on the valve stem, said sleeve being adapted at its upper end to engage the valve plug, said valve plug and sleeve constituting the stop means for arresting the lifting of the filler element relative to the valve stem.

11 11. A dispenser, as claimed in claim 10, wherein the valve plug is formed with a depending annular drip-flange defining a recess in the bottom of said valve plug, the upper end of said mounting sleeve playing within the confines of said recess and free from contact with said flange.

12 12. In a dispenser, a container for a supply of liquid, valve mechanism adapted to dispense from the container successive charges of the liquid, said valve mechanism comprising a valve body in the bottom of said container, said body having a discharge bore therein opening downwardly therefrom, a lift valve including a valve plug downwardly movable to obstruct said discharge bore upon the gravitating descent of said lift valve and upwardly movable to clear said discharge bore upon the elevation of said lift valve, a valve stem extending downwardly from said valve plug and out of said discharge bore, said valve stem having a valve head thereon at the lower portion thereof, means associated with the valve stem for elevating said lift valve, said means including a breast member adapted to be engaged by the rim of a receptacle into which a charge of liquid is to be dispensed, said breast member embodying a filler element open at the top thereof for the reception of liquid from said discharge bore and having a valve opening in the bottom thereof for the egress of such liquid from said element into said receptacle, a sleeve disposed coaxially of said filler element, said filler element being mounted on said sleeve, said sleeve being slidably mounted on said stem, said filler element being adapted to descend along the stem by gravity, said valve head being adapted to be engaged by the descending filler element to arrest its descent and to close the valve opening therein, said sleeve being adapted at its upper end to engage the valve plug, said valve plug and sleeve constituting stop means adapted to arrest the lifting of said filler element relative to said stem after the valve opening in the ascending filler element has cleared the valve head on said stem.

13 13. In a dispenser, a container for a supply of liquid, valve mechanism adapted to dispense from the container successive charges of the liquid, said valve mechanism comprising a valve body in the bottom of said container, said body having a discharge bore therein opening downwardly therefrom, a lift valve including a valve plug downwardly movable to obstruct said discharge bore upon the gravitating descent of said lift valve and upwardly movable to clear said discharge bore upon the elevation of said lift valve, a valve stem extending downwardly from said valve plug and out of said discharge bore, said valve stem having a valve head thereon at the lower portion thereof, means associated with the valve stem for elevating said lift valve, said means including a breast member adapted to be engaged by the rim of a receptacle into which a charge of liquid is to be dispensed, said breast member embodying a filler element open at the top thereof for the reception of liquid from said discharge bore and having a valve opening in the bottom thereof for the egress of such liquid from said element into said receptacle, a sleeve disposed coaxially of said filler element, said filler element being mounted on said sleeve, said sleeve being slidably mounted on said stem, said filler element being adapted to descend along the stem by gravity, said valve head being adapted to be engaged by the descending filler element to arrest its descent and to close the valve opening therein, said sleeve being adapted at its upper end to engage the valve plug, said valve plug and sleeve constituting stop means adapted to arrest the lifting of said filler element relative to said stem after the valve opening in the ascending filler element has cleared the valve head on said stem and an annular drip-flange depending from said valve plug substantially coaxially relative to said sleeve, said drip-flange having an inside diameter substantially greater than the outside diameter of said sleeve.
